HUGO SCHRÖDER, OF ESSEN, GERMANY

COKE OVEN

Application filed October 18, 1926, Serial No. 142,240, and in Germany August 5, 1926.

My invention relates to improvements in coke ovens, and more particularly in horizontal coke ovens provided with vertical flues, in which the flues located near the ends 5 of the oven are more intensely heated than the flues located at the middle of the oven. One of the objects of the improvements is to provide an oven of this type in which the heating means are simple in construction, 10 and with this object in view my invention consists in constructing the heating means so that only the flues located at or near the ends of the oven are intensely heated, while the flues located between said intensely heated 15 flues are uniformly and less intensely heated. Thus complicated means for regulating the temperature of the individual median flues are dispensed with. I have found that by thus regulating the intensity of the heating 20 means within the flues the coke is uniformly heated throughout the length of the oven, the higher intensity of the heating means of the end flues compensating the loss of heat by radiation.

25 For the purpose of explaining the invention several examples embodying the same have been shown in the accompanying drawing, in which the same letters of reference have been used in all the views to indicate 30 corresponding parts. In said drawing,

Fig. 1 is a longitudinal sectional elevation showing the oven and one of the regenerators,

Fig. 2, is a section taken on the line 2—2 35 of Fig. 1,

Fig. 3, is a detail sectional view showing a part of a regenerator of modified construction;

40 Figs. 4 and 5, are diagrammatical views showing modifications of the fuel supply pipes;

Fig. 6 is a fragmentary sectional view, illustrating the passages for introducing gas into the outer and intermediate flues; and

45 Figs. 7 and 8 are fragmentary sectional views showing modifications in the construction of the passages for supplying gas to the outer and inner flues.

In the example shown in Figs. 1 and 2, the 50 oven comprises coking chambers s , flues h ,

and regenerators a^1 , a^2 located below the coking chambers. As shown the regenerators are divided by horizontal partitions c into upper and lower sections a^1 and a^2 connected with each other at their inner ends. The fresh 55 air is supplied to the lower section a^1 through an inlet d made at the bottom of the end wall b , and the preheated air is supplied to a passage f communicating with the flues through passages n and with the regenerator through a passage or opening e made in the top wall 60 of the regenerator adjacent to the end wall b , the supply of air to the passage f being regulated by means of a slide g adapted to be moved longitudinally of the passage f . 65 As appears more particularly from the right hand part of Fig. 1, the first and second flues h^1 and h^2 communicate with a gas supply passage i , which is independent of the gas supply passage k connected with the median flues 70 h , and both supply passages may be independently regulated for example by means of cocks q^1 and q^2 .

In the operation of the oven the air is admitted through the inlet b to the lower section a^1 of the regenerator, and after being partly preheated therein it rises into the upper section a^2 . After being preheated within the said section it rises through the passage e and into the passage f . But a comparatively large proportion of the air flows directly through the air ducts or passages m and n and into the first and second flues h^1 and h^2 , because it is admitted thereto without first undergoing a change of direction. 75 The air flowing into the passage f is deflected from vertical direction to horizontal direction and thereafter it is again deflected from horizontal direction to upward direction, so 80 that the flow of the air is retarded to some extent and a reduced amount of air is admitted to the median flues h . Further, a comparatively large amount of gas is supplied to the first and second flues h^1 and h^2 . Thus 85 comparatively intense flames are produced within the flues h^1 and h^2 , which compensate the loss of heat by radiation through the end walls of the ovens. Thus loss of heat from the median flues h is avoided, and it is not necessary to provide additional means for 90 95 100

more intensely heating any of the median flues.

By means of the slides g the air supply to all the flues h , h^1 and h^2 is regulated, but in any position of the said slides the outer flues h^1 and h^2 receive a comparatively large amount of air.

An important feature of the new construction consists in that no special regulating means are needed, and that the increased supply of air to the outer flues is effected exclusively by the construction of the oven. Another important feature consists in that the heating of the flues can be regulated in a simple way. By protecting the inner flues h against loss of heat by radiation, they are uniformly heated, so that they produce a uniform draft causing a uniform admission of air. Thus the oven is to a large extent automatically regulated, and the regulating slides located on the flues may be set once for all, and they are not needed any more for compensating the loss of heat by radiation. Thereby the work of the attendant is made comparatively simple.

Further, the oven has a high efficiency by reason of the increased economy of the chequer work of the regenerator and the reduced loss of heat from the regenerator by radiation, the said loss by radiation being small, because the bottom part of the end wall is exposed only to the waste gases which have already passed through the top and bottom parts of the chequer work, or to cold air.

The construction of the regenerator in two sections is important because thereby the temperature within the passages for the attendant is reduced.

In Fig. 3 I have shown a modification of the means for regulating the flow of air to the flues, the slide g^1 being provided with means for regulating the admission of air to the passage f . As shown the said slide is provided with an upwardly directed rib o co-operating with a rib p depending from the top wall of the passage f . Thus, when shifting the slide g^1 to the left for reducing the supply of air through the passage e and to the flues h^1 and h^2 , the passage f is simultaneously obstructed, so that also the supply of air to the flues h is reduced.

In the example so far described independent passages or pipes are provided for supplying fuel to the outer flues h^1 , h^2 and to the inner flues h . In Figs. 4 and 7 I have illustrated a gas supply pipe t which is common to both sets of flues, and which is formed, between the second and third flue, with a double knee r by means of which the resistance of the pipe to the movement of the gas is increased, and a comparatively large amount of gas is supplied to the first and second flues h^1 and h^2 . In the modification shown in Figs. 5 and 8 the same result is obtained by reducing the pipe t' , which is com-

mon to both sets of flues, in cross-section as at t^2 at the rear of the second flue.

I claim:

1. A coke oven, embodying a horizontal coking chamber, a series of vertically extending heating flues arranged along a side of the coking chamber, horizontal air-distributing conduits underneath the coking chamber and ducts leading from the conduits to the flues, vertical air inlet passages adjacent the opposite ends of said coking chamber respectively, and communicating directly with said conduits at the ends thereof of adjacent the ends of said coking chamber, means for supplying gaseous fuel to a plurality of the vertical flues adjacent each of the two opposite ends of said coking chamber, independent means for supplying gaseous fuel to the intermediate flues to provide for the heating of the end flues to a greater extent than the intermediate flues in order to compensate for loss of heat by radiation from the end flues and thus produce uniform heating throughout the oven structure, and valve means for controlling the flow of air through each of said inlet passages, said valve means comprising slide valves, and means cooperating therewith for simultaneously varying the cross section of each of said distributing conduits adjacent the inlet passage that communicates therewith.

2. A coke oven, embodying a horizontal coking chamber, a series of vertically extending heating flues arranged along a side of the coking chamber, horizontal air-distributing conduits underneath the coking chamber and ducts leading from the conduits to the flues, vertical air inlet passages adjacent the opposite ends of said coking chamber respectively, and communicating directly with said conduits at the ends thereof adjacent the ends of said coking chamber, means for supplying gaseous fuel to a plurality of the vertical flues adjacent each of the two opposite ends of said coking chamber, independent means for supplying gaseous fuel to the intermediate flues to provide for the heating of the end flues to a greater extent than the intermediate flues in order to compensate for loss of heat by radiation from the end flues and thus produce uniform heating throughout the oven structure, valve means for controlling the flow of air through each of said inlet passages, said valve means comprising slide valves arranged upon the bottoms of said horizontal distributing conduits so as to be movable across said inlet passages, a rib in each of said distributing conduits at a point adjacent the inlet passage that communicates therewith, the rib extending transversely to the distributing conduit and projecting downwardly from the top thereof, and a rib on each of said valve means projecting upwardly therefrom and extending

transversely to the distributing conduit and arranged to cooperate with the downwardly projecting rib in the same conduit therewith whereby to vary the cross section of the distributing conduit adjacent the inlet passage that communicates therewith simultaneously with the variation in the control of air flow through the inlet passage.

5 In testimony whereof I hereunto affix my
10 signature.
